UNITED STATES PATENT OFFICE.

WILLIAM M. LEVY, OF ST. LOUIS, MISSOURI.

SINGLE-TRIGGER MECHANISM.

SPECIFICATION forming part of Letters Patent No. 645,107, dated March 13, 1900.

Application filed September 5, 1899. Serial No. 729,499. (No model.)

To all whom it may concern:

Be it known that I, WILLIAM M. LEVY, a citizen of the United States, residing at the city of St. Louis, State of Missouri, have invented a certain new and useful Improvement 5 in Single-Trigger Mechanism, of which the following is a full, clear, and exact description, such as will enable others skilled in the art to which it appertains to make and use the 10 same, reference being had to the accompanying drawings, forming part of this specification, in which—

Figure 1 is a side elevational view, partly in section, of a portion of a gun provided with 15 my improved single-trigger mechanism. Fig. 2 is a top plan view thereof, showing some of the parts in horizontal section. Fig. 3 is a side elevational view as seen from the opposite side from that shown in Fig. 1 of the single-trigger mechanism, other associate parts 20 being shown in dotted lines. Figs. 4 to 9, inclusive, are diagrammatic views, in side elevation, of my improved single-trigger mechanism, showing the parts in different positions. 25 Figs. 4^a to 7^a, inclusive, are detail views of one of the tumblers, showing its position relative to the near tumbler illustrated in Figs. 4 to 7, respectively. Fig. 10 is a diagrammatic view of my improved single-trigger 30 mechanism, showing a slightly-modified form of the locking-pin. Fig. 11 is a top plan view of the thumb-slide. Fig. 12 is a detail view of the trigger and its extension. Fig. 13 is a diagrammatic view of my improved single-trigger 35 mechanism, showing the tumblers and sears made in one piece. Figs. 14, 15, and 16 are similar views of a different modification, showing the tumblers made in one piece in the form of a sliding block. Fig. 17 is a 40 detail view of the sliding block containing the tumblers. Fig. 18 is a cross-sectional view on line 18 18 of Fig. 14. Fig. 19 is a top plan view of the sliding block and the rear end of the sears, showing the same position of the 45 parts as illustrated in Fig. 16; and Fig. 20 is a top plan view of the sliding block, wherein the trigger has a free safety position.

This invention relates to a new and useful improvement in single-trigger mechanism for 50 guns having a plurality of barrels, the object being to enable the operator to successively release or trip the firing mechanism by the

manipulation of a single mechanism in the form of a trigger, or by the provision of suitable means said single-trigger mechanism 55 may be confined to the control of a single firing mechanism.

With this object in view the invention consists in the combination of a plurality of firing mechanisms and a single-trigger mechanism 60 adapted to cooperate successively with all of said firing mechanisms or with but one of said firing mechanisms.

The invention also consists in the arrangement, construction, and combination of the 65 several parts of my improved single-trigger mechanism, all as will hereinafter be more fully described and afterward pointed out in the claims.

In the drawings I have shown in Figs. 1, 2, 70 and 3 my improved single-trigger mechanism as applied to a well-known form of firing mechanism, which latter is illustrated solely for the purpose of showing the application of my device to a well-known construction; but 75 it will be obvious to those skilled in the art to which my invention relates that the improved single-trigger mechanism hereinafter described can be applied to any form of firing mechanism, and therefore I do not wish to be 80 understood as limiting myself to the particular form of firing mechanism shown.

In the drawings, A indicates what is known as the "frame," B the barrels, B' the fore-end carrying the barrels and pivoted to the forward end of the frame A at b, C the lifter arranged on the rear end of the cocking-shaft, (not shown,) D the hammer, E the sear, F the mainspring, G the bridle, H the trigger, I the stud, J the slide, K the thumb-piece, and L 90 the tang, all of said parts, with the exception of the stud, being practically of the usual and well-known construction of the firearm commonly called a "double-barrel hammerless shotgun." 95

The general construction and operation of a double-barrel hammerless shotgun is well understood and a detailed description here is hardly necessary, but for purposes of explanation may be briefly described as follows: The gun shown is of the breakdown type, and upon the release of the breech-locking mechanism by the manipulation of the top lever M the barrels swing on the pivot b, which, in

addition to actuating the ejecting mechanism, in general, also sets in motion the cocking mechanism, of which the lifter C, coöperating with the forwardly-projecting end of the hammer D, forms a part. The breech-locking lever and post N, which is rotated when the gun is thus broken through the instrumentality of the cam projection n on its upper end engaging with a slide O, fitted in a groove 10 under the tang and abutting at its rear end against the slide J, forces said slide J rearwardly and with it its attached thumb-piece K, so that the tooth j on the rear end of this slide passes out of a notch, which I will mark 15 2, in the tang and into a notch which I will mark 1. A third notch 3 behind the notch 1 for coöperating with the tooth j and in another position of the parts will be hereinafter described. The shells are now introduced 20 into the breech of the gun and the barrels closed. In the mechanisms heretofore used, which employ the essential characteristics of the several parts above mentioned, two triggers were employed, one for each firing 25 mechanism, and in the position where the tooth j was forced into the notch 1 those triggers were locked against movement, and to unlock the triggers it was necessary to move the thumb-piece K forwardly into the notch 30 2 to unlock the triggers, which upon the gun being broke would result in the automatic restoration of this device. If, however, the tooth were moved rearwardly into engagement with the notch 3, this device would be 35 thrown beyond the limit of movement of the slide O and would not be actuated thereby upon the breaking of the gun, and in such third position the gun can be loaded and fired without moving the thumb-slide K, this position 40 of the thumb-slide being what is known as the "independent safety" position. This being the general design and operation of the gun shown in Fig. 1, although, as stated before, I do not wish to be understood as limiting my improvement in its application to a 45 gun having these general characteristics, nor, indeed, to the type of gun shown, as it can as well be applied to three-barrel guns or hammer-guns or any other form of firearms, I will 50 now describe the construction and operation of my improved trigger mechanism used in connection therewith.

a indicates a pivot-block upon which the trigger II is pivotally mounted, said trigger 55 being provided with a rearwardly-extending tailpiece h. (More clearly shown in Fig. 12.)

The slide J carries a pivot-block j', in which is pivoted a rocking frame J', formed with an opening which receives the stud I, said 60 stud practically telescoping into said rocking frame. The forward end of frame J' is provided with an abutment or stop-nose j², while a projection j³ extends rearwardly from said rocking frame, between which and the slide 65 J is interposed a spring j⁴, whose energy is exerted to hold the rocking frame in what I will term its "forward" position or in a posi-

tion wherein the nose j² abuts against the slide J and holds the frame stationary.

The stud I, which telescopes in the rocking frame J', carries on its lower end a slide or some suitable antifriction device, a roller i being shown in the drawings, which rests upon and coöperates with the upper face of the trigger extension h. A spring interposed between a shoulder on the lower end of stud I and the lower face of the rocking frame J' tends to hold the slide or roller i in constant engagement with the trigger extension, said spring serving, in addition to performing the above function, as a trigger-spring to hold the trigger in its forward position.

Q indicates a tumbler mounted on the pivot-bolt of the trigger; but this is unimportant, as a separate pivotal connection for this tumbler would answer as well, which tumbler, as shown in Figs. 2 and 3, has a spring q engaging with its free end, which spring tends at all times to elevate said tumbler. The rear or free end of tumbler Q is recessed or formed with an opening or series of openings, each of which coöperates with a lateral projection I' on the lower end of the stud I, which projection, as shown in the drawings, consists of an extension of the spindle on which the antifriction-roller i is mounted.

In describing the recesses in the movable end of tumbler Q, I will refer to the rearmost as q', in which the projection I' in two positions of the stud I is adapted to move freely without actuating the tumbler. The next recess, which I have marked q², is formed in a depending stepped projection, with which the lateral projection I' is adapted to engage in one of the positions of the slide J, so that upon the actuation of the trigger said tumbler will be positively raised. The next recess I have marked q³ and which is in advance of the stepped projection. In this recess the lateral projection I' is adapted to move freely after the tumbler Q is raised and without actuating said tumbler.

R indicates a companion tumbler arranged on the opposite side of the trigger extension and stud I, which companion tumbler is shown as pivoted coincidently with the trigger, but whose pivotal point of attachment, as is obvious, can be at some other place. This tumbler R is provided at its free end with an inverted-T-shaped recess or opening, the rearmost pocket of which I have marked r', in which pocket a lateral projection coincident with the projection I' and on the lower end of the stud I is designed to be received to operate the tumbler R independently of its companion tumbler. The next or middle recess r² is of such height that the lateral projection I' can in two positions of the stud I operate freely therein without actuating the tumbler R. The next recess or pocket is marked r³ and is located in advance of the recess r², and in this recess r³ the lateral projection I' is adapted to be received to operate the tumbler R after disengagement from

the recess q^2 of the tumbler Q and when in alignment with the recess q^3 .

Each of the sears E of the different firing mechanisms is shown as pivoted in the bridles G, their rear ends being provided with inwardly-extending projections f, which respectively rest upon the upper edges of the tumblers Q and R. The forward ends of sears E coöperate with recessed projections d, extending from the hubs of the respective hammers D. The hub coöperating with the sear which is controlled by tumbler Q is provided with a "lifting portion" d', as I will term it, whose function is to hold the rear end of its coöperating sear in an elevated position when the hammer on which it is arranged is in a forward position.

For the sake of distinction I will call the tumbler Q the "primary" tumbler and the tumbler R the "secondary" tumbler. The primary tumbler controls the hammer of the right barrel, while the secondary controls that of the left; but this arrangement may be reversed, as is obvious. The hub of the hammer controlled by the primary tumbler is provided with the lifting projection d', while the hub of the hammer controlled by the secondary tumbler may or may not be provided with a similar lifting projection. In a two-barrel gun this lifting projection is not necessary in the secondary mechanism, but would be if a third mechanism or more were to be successively thrown into action.

I will now describe the operation of my improved single-trigger mechanism. Assuming the hammers to be in a firing position and the slides in the position shown in Fig. 8, which position is the first one occupied by the parts after the gun is broken. The gun now being closed, it will be obvious that any actuation of the trigger will result merely in elevating the trigger extension and telescoping the stud I into the rocking frame, the lateral projections I' moving freely through space or recesses q' and r^2 . The sear projections f terminating short of the trigger extension said extension, if elevated, would pass between them. When the parts are in this position, the thumb-piece K is in the position shown in Fig. 11, wherein the word "Safe" on the tang will be exhibited through an opening in the forward end of said thumb-piece, indicating that the mechanism is safe or that it cannot be fired by pulling the trigger. The tooth j, engaging the notch 1, tends to hold the parts in this position. If it is desired to fire the right barrel or the right and left barrels successively, the thumb-piece K is moved forward until the letters "R" and "L" (indicating right and left) are exhibited through the opening in the thumb-slide. The tooth j will have now engaged with the notch 2 in the tang, and this forward position of the slide J will have trailed the lower end of the stud I over the trigger extension until one of its projections I' is received by the recess q^2 and arrested against further forward movement by

the depending stepped projection of the tumbler Q, such arrest of the forward movement of the stud tilting or rocking the pivoted frame J' to an abnormal position, as shown in Fig. 4. By pulling the trigger when the parts are in this position the projection I' being in its engaged position relative to the primary tumbler will elevate said tumbler, the stud telescoping in the rocking frame, said elevated tumbler carrying with it the rear end of the sear of its controlled firing mechanism. The forward end of the actuated sear releasing its hammer said hammer will be impelled by its mainspring to deliver an impacting blow on the firing-pin or other device. When the tripped hammer reaches its forward position, its lifting projection d' will engage the forward end of its sear and hold the rear end of said sear above the limit of movement of the controlling tumbler, which position of the parts is shown in Fig. 5. The trigger being relieved from rearward pressure permits the spring around the stud to force the trigger extension downwardly and the trigger forwardly until the lateral projection I' passes downwardly out of engagement with the stepped or shouldered projection containing the recess q^2 , the tumbler Q being held in its elevated position by the spring q, and when the projection I' on the stud is free to move forward under the action of the spring, it does so and is received in the recess r^3 of the secondary tumbler, as shown in Fig. 6. When the trigger is pressed the second time, its extension elevates the stud, telescoping it into the rocking frame, and the lateral projection on the stud carries with it the secondary tumbler, said lateral projection being free to move in the recess q^3 of the primary tumbler, and this secondary tumbler elevates the rear end of its coöperating sear, so that the forward end of said sear is depressed away from the shoulder of the hammer, which it has heretofore held retracted, so that said hammer may now move forward, impelled by the action of its mainspring, to deliver its impacting blow. This position of the parts is illustrated in Fig. 7. Both barrels having now been fired, it is necessary to reload the gun, and to do this the gun is broken, which act, as heretofore described, through the instrumentality of the cam-like projection n on the lever and post N, operating against the slide O, forces the slide J rearwardly, said slide J carrying the stud, so that its lateral projections I' are in registration with the recesses q' and r^2 of the tumblers. This is what is known as the "safe position," the one from which we started in describing the operation of the mechanism.

It is frequently desirable to fire but one barrel of the gun, and while this one barrel is being fired to lock the firing mechanism of the other against movement from external means, and to accomplish this the slide J is designed to be moved to a third position, wherein its tooth j is received by the notch 3 of the tang. When the parts are in this po-

sition, (shown in Fig. 9,) the lateral projection on the stud is received in the recess r' and upon every operation of the trigger will elevate the secondary tumbler, but move freely through the recess q' of the primary tumbler. To indicate this position of the parts, the word "Left" is impressed on the tang and is designed to be seen through the opening in the thumb-piece when the tooth j is in the third notch, as is well understood. The slide K, being in this rearmost position, is beyond the reach of the slide O, actuated when the gun is broken; and therefore the left barrel can be loaded and fired in the usual manner without operating the thumb-piece, the firing mechanism for the right barrel remaining cocked, but inoperative under these conditions.

From the above it will be seen that the thumb-piece is susceptible of manual operation to place its connected slide J in either of three positions, the first of which I will call "safe," wherein the operation of the trigger will be idle—that is, neither of the tumblers will be operated; the second or forward position, wherein the operation of the trigger will move the primary tumbler, and the next operation of the trigger while the slides are in the same position will move the secondary tumbler. From this forward position the slide is automatically returned to safe when the gun is broken. The third position is one in which by operating the trigger one of the tumblers will be moved, the other tumbler remaining stationary or being unaffected by the operation of the trigger when the parts are in this position.

While I have mentioned herein that the primary tumbler is identified with the right barrel of the gun and the secondary with the left barrel, yet it will be obvious that the position of these tumblers can be changed so that the left barrel will be the first fired and the right the second. It will also be obvious that instead of having one tumbler on each side of the trigger both of the tumblers can be on the same side, in which event but one lateral projection I' would be necessary instead of two, as shown in the drawings. In fact, in the above description I have frequently referred to this lateral projection I' in the singular number and as being one and the same instead of differentiating the projections on each side of the roller and giving each a separate reference-letter. Furthermore, while I have shown my device as employed in connection with a gun having two barrels it will be obvious that my improved single-trigger mechanism can very readily be employed in connection with guns having three or more barrels designed to be fired successively and that to accomplish this all that is necessary is the provision of an additional tumbler for each additional firing mechanism or the addition of steps to the tumbler herein shown.

In Fig. 10 I have shown a slightly-modified construction in which, instead of permitting

the free movement of the trigger when the parts are in a safe position, I extend the stud through the rocking frame, so that when the gun is broken and set to "safe" the stud is in line with a projection l on the tang and prevents the trigger from being moved. When the slide is moved forwardly, as shown in Fig. 10, the stud is in line with recess l' in the tang, which permits the trigger to be operated to elevate the primary tumbler, after which the rocking frame is tilted by its spring, as heretofore described, so that the lateral projection is received in the forward recess of the secondary tumbler, and another operation of the trigger will result in the elevation of this second tumbler to fire the other mechanism, as heretofore described. When the stud is in line with the recess l'' to the rear of the projection l , only the secondary tumbler can be operated, as heretofore described, the primary tumbler when the parts are in this position remaining stationary. It is of course understood that when the slide is in this rearmost position it is beyond control of the breech-locking mechanism and the stud is not thrown to a safe or locked position when the gun is broken.

In Fig. 13 I have shown another modification, in which the tumblers are attached directly to the rear ends of the sears, so that the tumblers and sears move in unison. The operation of this construction is identically the same as that heretofore described, where the tumblers and sears were made in separate pieces.

In Figs. 14 to 20 I have shown another modification, in which a sliding block S, pivotally mounted on the lower end of the stud and riding on the trigger extension, is provided with recesses and projections answering the purpose and function of the separate tumblers heretofore described. In fact, this sliding block is a tumbler coöperating with the trigger and the firing mechanisms to engage the trigger with one of said mechanisms, and after said mechanism is operated the lifting projection on the hammer changes the position of said firing mechanism relative to said sliding block, enabling said sliding block to move forward automatically under the action of the spring j' to coöperate with the next firing mechanism and positively engage the same with the trigger, when the operation of said trigger will operate said second mechanism. In this construction, as in the others heretofore described, it is the changed position of the mechanism first fired or one element thereof—as, for instance, the rear end of the sear—which enables the single-trigger mechanism to automatically operate to engage with the other mechanism to be fired. In the construction shown in Figs. 14 to 19 the rear ends of the sears are provided with the usual lateral projections f , and the safety-stud preferably coöperates with the web or projection l and recesses l' and l'' in the tang, as described in connection with Fig. 10.

When the stud is in its locked position, the front face of the projection on the right sear is in engagement with the projection or shoulder s of the sliding tumbler-block and over 5 the face s' of said block, while the projection on the left tumbler is opposite a recess s^2 in said sliding block. Assuming now that the slide J is moved forward, the upper end of the stud is thrown opposite the recess l' and 10 the spring j' placed under tension. By pulling the trigger the face s' of block s forces the right sear upwardly to operate its controlled firing mechanism, and after said sear is elevated it is held in such raised position 15 by the lifting-shoulder d' of the hammer on a plane higher than the height of the shoulder s . The spring around the stud now forces the block and the trigger downwardly, so that the shoulder s occupies a position beneath 20 the elevated sear, at which time the spring j' on the rocking frame forces the block forwardly on the trigger extension and places the face s^3 of said block under the left sear. By pulling the trigger when the block is in this 25 position the rear end of the left sear will be elevated and its controlled mechanism operated. As the right sear occupies a position above and behind the shoulder s , it will not be operated when the block is raised as last described. 30 When the gun is broken, the parts are automatically restored to their first position. If it be desired to fire the left barrel only, the slide J is moved rearwardly, so that the stud is placed opposite the recess l^2 , which causes the face 35 s^4 of the block to occupy a position under the left sear, while the right sear is opposite a space or cut-away portion s^5 of the block. Being beyond the control of the breech-locking mechanism in this position, the left barrel 40 can be loaded and fired, the right barrel meanwhile remaining cocked, but unaffected by the firing of the left. Of course it is obvious that the recesses l' and l^2 can be dispensed with in the tang in this construction. 45 in the same manner as shown in Figs. 4 to 9, all that is necessary to effect the safety position of the gun being the elongation of the cut-away portions s^2 and s^5 , so that they will overlap each other, and when the gun is 50 broken the sears will occupy positions opposite the spaces in this sliding block, as shown in plan view in Fig. 20. The movement forwardly in this construction will result in the right sear engaging the shoulder s and occupying a position over the face s' , and when 55 the trigger is pulled the right barrel will be fired, the left sear in such operation being received freely in the rear end of the cut-away portion s^2 . When the block is automatically 60 moved forward, as above described, the face s^3 is brought under the left sear. To fire the left barrel, the block is moved rearwardly until the face s^4 is brought under the left sear, in which position of the block the right sear 65 is still opposite the cut-away portion s^5 , as above described.

I am aware that minor changes in the ar-

rangement, construction, and combination of the several parts of my device can be made and substituted for those herein shown and described without in the least departing from the nature and principle of my invention.

Having thus described my invention, what I claim, and desire to secure by Letters Patent, is—

1. The combination with a plurality of firing mechanisms, of a single trigger therefor, tumblers interposed between said trigger and firing mechanisms, a shiftable device in engagement with the trigger and normally out of engagement with the tumblers, and means for moving said device into a position to engage one or the other of said tumblers; substantially as described.

2. The combination with a plurality of firing mechanisms in which are included hammers and sears, of a single trigger common to all of said mechanisms, independently-operable tumblers for operating the different sears, and means for engaging the single trigger successively with the different tumblers; substantially as described.

3. The combination with a plurality of firing mechanisms in which are included hammers and sears, of a single trigger common to all of said mechanisms, tumblers co-operating with said sears and said trigger, and a manually-operable device for engaging said trigger with, or disengaging said trigger from, one or all of said firing mechanisms; substantially as described.

4. The combination with a plurality of firing mechanisms, of a single trigger common to all of said mechanisms, devices interposed between said single trigger and said mechanisms, and manually-operable means designed to co-operate with the trigger and said devices whereby, when said means are in one position the successive operations of the trigger will successively operate the different firing mechanisms, said means in another position causing the engagement between said trigger and but one of said firing mechanisms through said devices; substantially as described.

5. The combination with a plurality of firing mechanisms, of a single trigger common to all of said mechanisms, independently-operable tumblers common to the respective firing mechanisms, and to the single trigger, and a manually-operable device in engagement with the trigger for engaging said trigger with one of said tumblers, whereby, when the trigger is operated, the engaged tumbler only is moved; substantially as described.

6. In a breakdown gun, the combination with the breech-locking mechanism, of a slide which may be controlled or thrown out of control of the breech-locking mechanism, a depending stud or projection carried by said slide, a plurality of independently-movable tumblers formed with shoulders and recesses, which co-operate with said depending stud or projection, and a single trigger for engaging and co-operating with said depending stud or

projection and with said tumblers; substantially as described.

7. In a breakdown gun, the combination with a plurality of firing mechanisms, of a single trigger for operating all of said mechanisms independently of each other, a plurality of tumblers common to said single trigger, but operable independently thereby, said tumblers forming part of the several firing mechanisms, a notched tang, a slide arranged therebeneath and provided with a tooth for engaging notches in the tang to hold said slide and its associate parts in different positions, a rocking frame mounted on said slide, a spring-pressed stud carried by said frame for causing successive engagements between the trigger and the tumblers, and a slide-bar extending from the breech-operating mechanism into position to shift the slide and its carried parts when said slide is in a forward position upon the breaking of the gun; substantially as described.

8. The combination in a breakdown gun, of a breech-locking mechanism, an independent slide operated thereby and having a locked position to the rear of the position where it is engaged by the breech-locking mechanism, a depending stud on said slide, a tumbler which engages the slide-stud in its rear position, and a trigger for operating said stud; substantially as described.

9. In a breakdown gun, the combination with a breech-locking mechanism and a plurality of firing mechanisms which include independently-operable tumblers, a single trigger common to all of said tumblers, a slide which is movable from one of its positions by the breech-locking mechanism, a device carried by said slide and in engagement with the trigger, which device is adapted to engage one of said tumblers or all of said tumblers successively, and an externally-arranged thumb-piece connected to said slide and designed to be manually operated, said thumb-piece operating with indexes, whereby the position of said slide and its carried parts relative to the tumblers may be determined; substantially as described.

10. The combination with a plurality of firing mechanisms, of a single trigger common to all of said mechanisms, tumblers interposed between said trigger and mechanisms, a slide, a frame pivoted to said slide, a spring-pressed rod carried by said frame, an extension on the trigger which is engaged by the lower end of said rod, and lateral projections extending from the lower end of said rod and coöperating with shouldered recesses in the tumblers; substantially as described.

11. The combination with a hammer carrying a lifting projection, of a sear, a tumbler for disengaging the sear from the hammer, the lifting projection of the hammer holding the sear out of engagement with the tumbler when said hammer is tripped, a spring for holding the tumbler in an elevated position after the sear trips the hammer whereby the

connecting-stud may pass from engagement with the tumbler, a trigger coöperating with said tumbler and a connecting medium between the trigger and the tumbler; substantially as described.

12. The combination with a trigger provided with an extension, of a spring-pressed stud slidably arranged on said trigger extension, a yielding rocking frame in which said stud is slidably mounted, a slide which carries said frame, lateral projections on the lower end of said stud, primary and secondary tumblers provided with shouldered recesses for coöperating with said lateral projections, sears which are designed to be engaged by said tumblers, hammers which are tripped by said sears, and a lifting projection on the hammer tripped by the sear of the primary tumbler; substantially as described.

13. The combination with the tang, of a slide J arranged therebeneath, a spring-pressed rocking frame J' mounted on said slide, means for arresting the movement of said frame in one direction, a stud slidably fitted in a bore in said frame, a roller carried by the lower end of said stud, lateral projections extending from the lower end of said stud, tumblers, with which said lateral projections coöperate, a trigger provided with an extension for receiving the stud-roller, and a spring interposed between the rocking frame and the stud for holding said roller in engagement with the trigger extension and said trigger in a forward position; substantially as described.

14. The combination with a firing mechanism, of a trigger, a tumbler common to said trigger and said firing mechanism, and a movable slide carrying a stud with a projection for causing the engagement of said trigger with said tumbler, said tumbler being provided with recesses q' , q^2 , and q^3 , for coöperating with the projection on the slide-stud; substantially as described.

15. The combination with a firing mechanism, of a trigger for operating the same, a tumbler common to said trigger and said firing mechanism, and a slide carrying a stud with a projection for causing engagement between said trigger and tumbler, said tumbler being provided with recesses r' , r^2 and r^3 , for coöperating with stud projection; substantially as described.

16. The combination with the primary tumbler provided with recesses q' , q^2 , and q^3 , and a secondary tumbler, provided with recesses r' , r^2 and r^3 , of a slide carrying a stud with a projection for coöperating with said recesses, a single trigger for coöperating with said stud, and operating one or the other of said tumblers therethrough, and independent firing mechanisms which are operated by said tumblers; substantially as described.

17. The combination with a plurality of firing mechanisms including hammers and sears, of means for holding at least one of said sears, after its associate mechanism has been re-

leased, in a position different from that occupied by said sear before its connected mechanism was released, so that another firing mechanism can be operated only after the sear reaches its last-mentioned position, a single-trigger mechanism common to all of said firing mechanisms and independently-operable devices interposed between said trigger and sears for connecting or disconnecting said trigger with and from said sears respectively; substantially as described.

18. The combination with a plurality of firing mechanisms including hammers and sears, of independently-operable tumblers, movable with the different sears, means for holding one of said sears and its coöperating tumbler in a position, after the release of the firing mechanism controlled thereby, different from that occupied by said sear and tumbler before said mechanism was released, whereby the other mechanism can be fired only after the sear and tumbler first mentioned, are operated, and their position changed, and a single trigger coöperating with said tumblers

and their associate sears; substantially as described.

19. The combination with a plurality of firing mechanisms, of separately-operable releasing devices therefor, primary and secondary tumblers coöperating with said releasing devices, a single trigger coöperating with said tumblers, and means for holding the releasing devices of the firing mechanisms first operated, in a position different from that which it occupied before operation, that is, the primary tumbler is moved out of operative relation with respect to the trigger, permitting the establishment of operative relation between the trigger and secondary tumbler; substantially as described.

In testimony whereof I hereunto affix my signature, in the presence of two witnesses, this 31st day of August, 1899.

WILLIAM M. LEVY.

Witnesses:

RALPH KALISH,
A. S. GRAY,
